UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

GRIPPER MECHANISM.

1,079,590.

Specification of Letters Patent.

Patented Nov. 25, 1913.

Application filed January 2, 1913. Serial No. 739,701.

To all whom it may concern:

Be it known that I, ARTHUR BATES, a subject of the King of England, and resident of Leicester, Leicestershire, England, have 5 invented certain Improvements in Gripper Mechanisms, of which the following description, in connection with the accompanying drawings, is a specification, like reference characters on the drawings indicating like 10 parts in the several figures.

This invention relates to pulling-over or like machines and is an improvement in or modification of the invention described in the specification of prior United States Letters Patent No. 1,030,522, granted June 25, 15 1912 on application of Ronald F. McFeely and an object of the present invention is to improve the construction and operation of the gripper mechanism of the machine there- 20 in shown.

The machine of the prior patent is provided with a pair or set of grippers at each side of the shoe and also with a compensating or equalizing device for each pair of grippers 25 that permits each gripper of a pair to move during the closing movement or during the updraw movement of the grippers or during both the updraw and closing movement, relatively to the other gripper of the pair. 30 This enables the two grippers to be closed to different extents in order to accommodate the varying thickness of stock at different portions of the edge of the upper, such for example as the portion of the upper adjacent 35 to the toe cap, or to allow the two grippers unequal range of movement for equalizing the tension in order to provide for different amounts of stretching of the upper. In practice the equalizing or compensating de- 40 vice of said prior construction is, in my opinion, open to the further criticism that when used upon certain work, as for example with lasts having high or prominent toes the range of relative movement of the two 45 grippers of a side gripper mechanism is too limited, and accordingly a further object of the invention is to overcome this objection and to provide means for permitting a greater range of relative movement of the 50 two grippers than has heretofore been the case. In the machine of the prior patent the equalizing or compensating device was located at the lower end of the gripper-operat- 55 ing bar and within the lower part of the chamber formed by the gripper carriers.

This arrangement has been found in practice to be disadvantageous in view of the fact that the various other mechanisms connected to the gripper jaws are by necessity situated in this part of the chamber so that the range 30 of relative or equalizing movement that could be imparted to the grippers was undesirably limited and difficulty occurred when it was necessary to inspect the said device or to remove and replace it. Conse- 35 quently in accordance with a feature of this invention the gripper compensating or equalizing device is situated at a point considerably nearer the top of the updraw bar and within easy reach of the operator for re- 40 moval, inspection or other purposes. 45

An important feature of this invention consists in a gripper mechanism comprising two adjacent grippers or pairs of jaws and a single operating bar having one or more 50 pinions the opposite sides of which are connected respectively with said pairs of jaws. Preferably there are separate latches by which the two pairs of jaws have detachable engagement with their closing mechanism. 55 Accordingly for a pulling-over or like machine having a gripper mechanism comprising two adjacent grippers and a single bar for operating them there is provided between each gripper and the said bar a connector 60 having rack teeth and there is also provided a pinion or pinions mounted upon the said bar preferably at a point well above the jaw closing mechanisms and accessible to the operator and engaging the said rack teeth, 65 thus providing the gripper mechanism with a differential device whereby the two grippers may move relatively to one another to put different portions of the upper acted 70 upon under the same strain. It will be noted 75 that when the gripper-operating bar is up- drawn the pinion will also be updrawn and both connectors will move upward together and the jaws will close upon the work to pull it. If the stress upon the two grippers 80 is equal they will not move relatively but if the stress is not equal there will be relative movement until an equality occurs and dur- 85 ing this relative movement the pinion will rotate in such a manner that it tends to decrease the stress upon the one gripper and to correspondingly increase the stress upon the other gripper. It will thus be seen that 90 each connector operates in the opening and closing of its gripper and also in the pulling 95 100 105 110

movement independently of the other except that the speed and the extent of the movement of each is relatively appropriate to the part of the work upon which it is operating.

5 Preferably the differential compensating device is so arranged with reference to the grippers that its operation will not affect the force of the grip of the grippers. The features of the invention above indicated, together with the novel combinations of parts and details of construction disclosed in the accompanying drawings will more fully appear in connection with the following description of the illustrated embodiment of 10 the invention and will then be pointed out in the claims.

In order that the present invention may be more readily understood the gripper mechanism with its equalizing device as constructed according to the prior invention 20 has first been shortly described, and hereafter the preferred construction of gripper mechanism and equalizing device according to the present invention will be described 25 with reference to the accompanying drawings but it is to be understood that the invention is not to be considered as limited to the precise construction set forth.

In the drawings:—Figure 1 is a side elevation of so much of a pulling-over machine as is necessary to show the embodiment of the present invention in one of its side gripper mechanisms; Fig. 2 is a vertical transverse section of the forward gripper 30 member of a pair; Fig. 3 shows a horizontal cross section of the side gripper mechanism taken on the line 3—3 of Fig. 1; Fig. 4 shows a similar cross section on the line 4—4 of Fig. 1.

40 An operating bar 168 supports a gripper carrier comprising two blocks 25, 26 which are grooved longitudinally and placed together in such a manner as to form a long chamber, U-shaped in cross section, Fig. 4, 45 the open side of the chamber being closed by two cover plates 27, 28 secured to the blocks by screws. The block 26 has firmly secured to it the usual fixed gripper jaw 29, a movable jaw 30 being pivoted to the block at 31 50 and being provided with a tongue adapted to be engaged by a roll 32 mounted on the loose slide 33 which is normally moved to its lowest position by means of its own weight so that the roll 32 is normally inoperative 55 to close the gripper jaws. The slide 33 has formed on it a lug 34 which is engaged at certain times by a latch 35 which is pivoted to the lower end of a vertically movable slide or connector 36 and is turned toward 60 the lug by a spring pressed plunger as shown in dotted lines in Fig. 2 to enable the latch 35 to be disengaged from the lug 34. The tripper 204 before mentioned is pivoted at one end to the loose slide 33. By press-

ing upon the loose end of the tripper an ear 65 upon it is caused to force the latch 35 from under the lug 34 and allow the slide 33 to descend and open the jaws. In order that there may be relative movement between the connector 36 and the gripper casing the connector is recessed upon one side and a spring 38 is provided which bears at one end against the top of the recess and at the other end against a cross piece 39 riveted to the block 26 of the gripper casing. The spring 75 thus serves to hold the gripper casing in its lowest position which is determined by a ledge 40 which projects from the lower end of the connector 36 underneath the cross piece 39 as shown in Figs. 1 and 2. When 80 the power actuated lever 2 is in its lowest position the spring 38 is fully compressed and the connector 36 and latch 35 are so low that the latch is pressed by its spring plunger into position underneath the lug 34, 85 the loose slide 33 being then at the lowest limit of its movement. As the operating lever 2 rises it pulls up the bar 168 and also the connector 36 so that the latch hooks under the lug 34 and thereby raises the slide 90 33 thus causing the roll 32 to operate upon and close the jaw 30. After the jaw has been closed further upward movement of the latch 35 lifts the jaw and the block 26 because the roll 32 is unable to move upward 95 relatively to the tail of the jaw 30 and therefore the grippers not only close upon the upper but are thereafter lifted to stretch the upper by the continued movement of the lever 2 in the same direction upward.

100 The description thus far has related to one pair of the side gripper jaws shown in Fig. 1 or to one gripper, as will be expressed in some of the claims for convenience in designation of the mechanism, and it will be 105 understood that the construction and operation of the other pair of jaws, or gripper, as for example the left hand pair, is identical with that of the right hand pair and that there are, in fact, two separate connectors 110 36, as is plainly shown in Fig. 1, which are connected with the gripper operating bar 168 by a compensating and equalizing device constructed and arranged as follows: The upper portion of each of the connectors 115 36 is provided with teeth 42 that are arranged so as to face one another and leave a space between them, Figs. 1 and 3. Within this space the gripper operating bar 168 is located and is provided with pinions 44 that 120 are adapted to engage with the teeth on both connectors. The pinions and operating bar are maintained in engagement with said teeth by means of a cover plate 45, see Fig. 3, which is U-shaped in cross section and is secured to the operating bar by means of screws. By this compensating and equalizing connection movement imparted to the 125

gripper operating bar 168 will be transmitted through the pinions and toothed connectors 36 to the loose slides 33 that operate to close and uplift the grippers so that in the 5 event of different thicknesses of stock being gripped or in the event of the different parts of the upper seized by the right and left pairs of jaws, Fig. 1, stretching to different extents, said connectors and pinions will 10 permit the grippers to be closed to the required different degrees and also will allow different amounts of updraw movement to be imparted to the right and left pairs of grippers to correspond with the variation in 15 the stretch of the upper. The advantage of this equalizing or compensating device is two-fold, since it not only permits a greater range of relative movement of the grippers, but also allows, when the tension on one 20 gripper exceeds that on the other, the second gripper to move at a quicker rate than the operating bar 168 so that the tension on the upper is very quickly equalized. Further, it will be noticed that the operation of the 25 equalizing device does not affect the degree of compression of the spring 38 so that the limit of the grip of the jaws upon the work is not affected by the relative position of the two pairs of jaws.

30 Having described my invention, what I claim and desire to secure by Letters Patent of the United States is:

1. A machine of the class described having, in combination, with suitable operating 35 mechanism, a gripper mechanism comprising two adjacent grippers and a single bar for operating them, a connector located between each gripper and the said bar and having rack teeth, and a pinion carried by the said 40 bar and engaging the said rack teeth whereby the grippers are moved to do their work and also may move relatively to one another for the purpose specified.

2. In a machine of the class described, a 45 gripper mechanism comprising two adjacent grippers having rack toothed bars connected therewith, a single operating bar, and an equalizing pinion through which and said

toothed bars the operating bar is connected to the two grippers. 50

3. In a machine of the class described, a gripper mechanism comprising two adjacent grippers each having a separate connector bar 36 provided with rack teeth on its face adjacent to the companion bar, and a single 55 operating bar provided between said connecting bars with two pinions both engaging in the racks thereon.

4. In a gripper mechanism for pulling an upper over a last, a plurality of pairs of 60 jaws for engaging the upper of the same side of a shoe, separate closing mechanisms for said pairs of jaws including separate latches 204 each of which has detachable engagement with a closing mechanism, a single 65 operating means for lifting the jaws, and equalizing means whereby the several pairs of jaws are caused to put different portions of upper acted upon under the same strain.

5. In a gripper mechanism for pulling an 70 upper over a last, a plurality of pairs of jaws for engaging the upper of the same side of a shoe, separate closing mechanisms for said pairs of jaws, a single operating bar for lifting the jaws, separate connectors 75 extending from the jaws to said operating bar, and rack and pinion equalizing means between said bar and said connectors.

6. In a gripper mechanism for pulling an 80 upper over a last, a plurality of pairs of jaws for engaging the upper of the same side of a shoe, separate closing mechanisms for said pairs of jaws, a single operating bar for lifting the jaws, separate connectors extending from the jaws to said operating 85 bar, and equalizing connections arranged between the separate connectors and the operating bar and located above and separate from the said closing mechanisms.

In testimony whereof I have signed my 90 name to this specification in the presence of two subscribing witnesses.

ARTHUR BATES.
